[57] CLAIM

The ornamental design for a container closure or similar article, as shown and described.

DESCRIPTION

FIG. 1 is a top plan view of a container closure or similar article showing my new design;

FIG. 2 is a front elevational view, the rear elevational view being identical thereto;

FIG. 3 is a right side elevational view, the left side elevational view being identical thereto;

FIG. 4 is a bottom plan view;

FIG. 5 is an enlarged fragmentary sectional view taken along line 5—5 of FIG. 1; and

FIG. 6 is an enlarged fragmentary sectional view taken along line 6—6 of FIG. 1.

FIG. 1

FIG. 2

FIG. 3

FIG. 4

FIG. 5

FIG. 6
